UNITED STATES PATENT OFFICE

130,343

DESIGN FOR A BRACELET OR SIMILAR ARTICLE

Harry Reinstein, New York, N. Y.

Application October 13, 1941, Serial No. 103,749

Term of patent 3½ years

To whom it may concern:

Be it known that I, Harry Reinstein, a citizen of the United States, residing at New York, in the county of the Bronx and State of New York, have invented a new, original, and ornamental Design for a Bracelet or Similar Article, for which the following is a specification, reference being had to the accompanying drawing, forming part thereof, wherein—

Fig. 1 is a front elevational view of a bracelet or similar article showing my new design, and

Fig. 2 is a side elevational view thereof. The dotted line illustration is a continuation of the portion shown in full lines.

While I have shown my new design embodied in a bracelet or similar article, it is contemplated that the same may be embodied in similar articles of jewelry without departing from the spirit of my invention.

I claim:

The ornamental design for a bracelet or similar article, substantially as shown and described.

HARRY REINSTEIN.
